(57) **CLAIM**

The ornamental design for a desk mounted electrical outlet for power and/or data, as shown and described.

DESCRIPTION

FIG. 1 is a perspective view of a desk mounted electrical outlet for power and/or data showing my new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken line showing of power outlets in FIGS. 1, 2, and 6 represents environmental subject matter and forms no part of the claimed design. The bottom view is omitted and forms no part of the claimed design.

1 Claim, 4 Drawing Sheets

FIG. 1

FIG. 2

FIG. 3

FIG. 4

FIG. 5

FIG. 6
